(57) **CLAIM**

The ornamental design for an air jet ball game, as shown and described.

DESCRIPTION

FIG. 1 is a top, front, right-side perspective view of the air jet ball game;

FIG. 2 is a Front elevation view of the air jet ball game;

FIG. 3 is a rear elevation view of the air jet ball game;

FIG. 4 is a left-side elevation view of the air jet ball game;

FIG. 5 is a right-side elevation view of the air jet ball game;

FIG. 6 is a top plan view of the air jet ball game;

FIG. 7 is a bottom plan view of the air jet ball game; and,

FIG. 8 is another top, front, right-side perspective view of the air jet ball game shown in an environment of use.

The evenly spaced broken lines and the dot-dash broken lines in the drawings depict portions of the air jet ball game that form no part of the claimed design. The additional dot-dot-dash broken lines in FIG. 8 depict environmental subject matter only that forms no part of the claimed design.
